CLAIM

The ornamental design for a roll of pre-cut strips of kinesiology tape, as shown and described.

DESCRIPTION

FIG. 1 is a perspective view of the roll of pre-cut strips of kinesiology tape showing my new design;

FIG. 2 is a front view thereof;

FIG. 3 is a first side view thereof;

FIG. 4 is a rear view thereof;

FIG. 5 is a second side view thereof;

FIG. 6 is a top view thereof; and,

FIG. 7 is a bottom view thereof.

Broken lines in the form of “dash-dash” broken lines have been included to illustrate features that form no part of the claimed design. Broken lines in the form of “dash-dot-dot-dash” broken lines have been included to identify a border between what is claimed and what is not claimed.
